UNITED STATES PATENT OFFICE.

EDWARD B. JACOBSON, OF PITTSFIELD, MASSACHUSETTS, ASSIGNOR TO J AND B MANUFACTURING COMPANY, OF PITTSFIELD, MASSACHUSETTS, A CORPORATION OF MASSACHUSETTS.

IGNITION-TIMER.

1,383,263.

Specification of Letters Patent. Patented June 28, 1921.

Application filed February 28, 1919. Serial No. 279,743.

To all whom it may concern:

Be it known that I, EDWARD B. JACOBSON, a citizen of the United States, residing at Pittsfield, in the county of Berkshire and State of Massachusetts, have invented certain new and useful Improvements in Ignition-Timers, of which the following is a specification.

The present invention relates particularly to the rotary portion of ignition timing apparatus, and has for its object the provision of improvements in self-lubricating means carried by the rotor which will adequately lubricate the course of the rotor contact and avoid gumming, poor circuit connections and other evils commonly caused by the excessive use of fluid lubricants. A further object is the provision of means to prevent arcing of the electric current between the contactor carried by the rotor and the several contact-elements mounted in the casing.

Referring to the accompanying drawings, Figure 1 is a longitudinal vertical section of an ignition timer embodying the present invention in its preferred form operatively mounted upon a cam-shaft; Fig. 2, a cross-section of the same on a line intermediate the rotor portion and the face of the housing; Fig. 3, a side elevation of the rotor portion, the contact-arm being shown in section; and Fig. 4, a rear elevation of the rotor portion.

The mechanism herein illustrated is designed for use in connection with a four-cylinder explosive engine having a gear-driven cam-shaft operated by the main engine shaft, but it should be understood, however, that my invention is susceptible of application, with slight modification, to motors having any other number of explosion cylinders, and may be otherwise mounted and driven.

This invention may be adapted to any suitable form of housing or casing, the casing 1 herein illustrated being adjustably mounted on the front of the engine housing 2 and arranged to inclose the front end of a cam-shaft 3, which is preferably geared to the main engine shaft (not shown) and extends through a suitable opening in the wall of the engine housing.

The rear end of the casing 1 is open and seated in a circular recess 4 provided on the face of the engine housing 2, said recess

being adapted to prevent eccentric displacement of the casing. Forward displacement of the casing is prevented preferably by a spring clamp 5 removably secured at its rear end to a stud or bolt 6 fixed to the wall of the engine housing 2, and engaging at its opposite end the outer extremity of the reduced forward extension of the front of the casing, which has a central depression to receive a boss 7 provided on the clamp 5. Axial movement of the casing for regulating the time of ignition is controlled by a lateral arm 8 exteriorly mounted on the casing and provided with a bearing 9 to receive a control-rod (not shown).

Within the casing 1 is an insulation ring 10 provided at regular intervals with arcuate contacts 11, 11, which are embedded on its inner rim and suitably connected to separate terminals 12, 12, etc., arranged on the outside of the casing 1, for connection with the primary circuit of separate induction coils.

Mounted to rotate with the shaft 3 within the casing 1 is a metallic carrier 13 in the form of a sleeve which is normally secured against relative movement on the shaft by a transversely arranged removable pin 14 projecting through a suitable opening in the shaft and extending at one of its ends into a slot 15 provided on the outer rim of the carrier. The pin 14 is secured against end-wise displacement by a cup washer 16 fitted over the outer end of the carrier and inclosing the exposed end of the pin 14, the reduced outer end 17 of the shaft being projected through the cup washer 16 and suitably threaded to receive a pair of nuts 18, 19, which are employed in conjunction with a flat washer 20, carried on the reduced end of the shaft and engaging the face of the cup washer, to secure the latter in position.

The carrier 13, which rotates normally counter-clockwise, is provided with a lateral longitudinally arranged contact-arm 21 disposed in the plane of the insulation ring 10 and extending at its forward end into position adjacent the contact-elements 11, 11, etc., said forward end being arcuate in outline to afford an even clearance at all points between its outer face and the inner rim or traveled surface of the ring 10. The contact-arm 21 is arranged to carry at its forward end a movable contactor 22 for slidably en-

gaging the inner rim of the ring 10, the outer end of the contactor being arcuate in outline to conform to the surface of the ring. The contactor 22 preferably comprises a rectangular block of hardened steel adapted to move lengthwise in either direction within a slot of the same dimensions provided transversely in the forward end of the contact-arm and is provided with a round rearward extension 23 adapted to movably project into a bore 24 provided lengthwise in the body of the contact-arm and communicating with said slot in its forward end. Said extension 23 is provided with a reduced stem 25 which extends rearward through an opening of corresponding size in the rear wall 26 of the chamber within the contact-arm 21 formed by the bore 24 and beyond said wall and carries on its extremity in the rear of the contact-arm a removable taper-pin 27 fitted in a suitable transverse opening in the stem and adapted to operate as a stop for limiting the forward movement of the contactor 22 and its rearward extension 23. Within the bore 24 and surrounding the stem 25 is arranged a coil expansion spring 28 confined by the extension 23 and the rear wall 26 and operating to urge the contactor 22 forward into constant engagement with the inner-rim 30 of the ring 10.

The outer end of the contactor 22 is provided centrally with a deep seated transverse slot extending across its face and adapted to be filled with a suitable solid lubricant 29 such as graphite composition for lubricating the inner rim of the ring 10 and the faces of the contact-elements 11, 11, etc. A lubricant of this description maintains a smooth even surface on the traveled course of the insulation ring 10 without adhering in large quantities or interfering

with the operation of the several electric circuits, being adapted to effectually retard wear and to maintain an even bearing surface for engagement with the contactor 22. 45 The forward edge 30 of the contactor 22 is maintained in a sharpened state to cut through any particles of matter tending to accumulate and adhere upon the rim of the insulation ring 10. To avoid injurious arcing or sparking of the current passing between the contactor 22 and the several contact-elements 11, 11, etc., each time the circuit is broken as the contactor 22 leaves a contact-element, I provide a facing strip 31 50 of fiber or other suitable insulation secured to the rear face of the contactor 22, which is cut away for this purpose and provided with a longitudinal groove for seating a corresponding tongue 32 provided on the inner 55 side of the strip.

I claim:

In an ignition timer, the combination with a casing, contact-elements mounted in the casing, and a rotor portion mounted to rotate in the casing and having an arm arranged lateral to its axis, of a spring-pressed contactor carried by said arm and arranged to yieldingly engage the contact-elements successively, said contactor being provided at its outer end with a cutting edge formed by the intersection at an acute angle of its bearing face with its front side and adapted to remove deposits adhering to the surfaces of the contact-elements. 70

In testimony whereof I heretofore affix my signature in the presence of two witnesses.

EDWARD B. JACOBSON.

Witnesses:

LE ROY E. SHAW,
JNO. J. WHITTLESEY.
